UNITED STATES PATENT OFFICE

RICHMOND S. A. MOORE, OF RIDGEDALE, TENNESSEE.

BOX.

No. 810,341

Specification of Letters Patent.

Patented Jan. 16, 1906

Application filed September 2, 1905. Serial No. 276,896.

To all whom it may concern:

Be it known that I, RICHMOND S. A. MOORE, a citizen of the United States, residing at Ridgedale, in the county of Hamilton and State of Tennessee, have invented new and useful Improvements in Boxes, of which the following is a specification.

The invention relates generally to an improvement in boxes, and particularly to a box constructed to guard the original condition of its contents.

The main object of the present invention is the production of a box adapted for service as a container, the construction providing against reuse of the box, so that its original contents are insured when in unbroken condition.

The details of structure of the present invention will be described in the following specification, reference being had particularly to the accompanying drawings, wherein—

Figure 1 is a vertical central section of my improved box, showing the cover in place thereon. Fig. 2 is a transverse sectional view taken through the neck-lugs. Fig. 3 is a vertical central section of the cover removed and illustrating particularly the locking-spring.

Referring to the drawings, wherein like parts are designated by like numerals of reference throughout the several views, my improved box comprises a body 1 and a neck 2, rising therefrom and of less diameter than the body, the laterally-extending ledge joining the body and neck being thickened at 3 to provide for supporting the cover. The neck is formed at diametrically opposite points with circumferentially-arranged ribs 4, one of which cooperates with a vertically-extented abutment 5, projecting from said rib 40 toward and in contact with the thickened portion 3 of the box. The abutment 5 is positioned at one terminal of one rib and is preferably equal in thickness to the thickness of the rib, so that said rib is practically a right-angled member with the short arm extending vertically from the thickened portion 3 of the box, while the long arm projects circumferentially of the box. The upper edge of the neck-wall is recessed at 6 to receive a lid-plate 50 7 to initially close the box-body.

8 represents a cover circumferentially co-extensive in diameter with the body 1 and of a height to project slightly above the neck 2 when in operative position. The cover comprises a top-plate 9 and a depending circular wall 10, the latter seating its lower end in a

notch 11, formed in the outer edge of the thickened portion 3 of the body. The cover-wall 10 is provided at diametrically opposite points with inwardly-extending lugs 12 of a length to contact with the outer surface of the neck 2 of the box when the parts are in co-operative relation. The lugs are so positioned relative to the height of the cover that when the latter is in operative relation to the box said lugs are in a plane immediately below the ribs 4 on the neck.

13 represents the spring-holding plate designed to be secured to the vertical wall of the box-cover intermediate the lugs 12 and below the same. The plate is provided with upwardly-projecting arms 14, between which is supported one terminal of a coiled spring 15, the opposite or free terminal of which is of a length to extend to the abutment 5 when the parts are in co-operative relation, pins 17 joining the arms 14 on opposite sides of the spring-leaf to prevent accidental or independent movement of the spring at this point.

By this construction it will be noted that the spring-leaf is arranged on edge with relation to the vertical dimension of the cover, whereby to resist strain incidental to the parts hereinafter described. In assembling the parts, assuming the box to be properly filled and the lid 7 in place, the cover 8 is positioned to inclose the neck 2, its lugs 12 being arranged intermediate the ribs 4. The cover is now turned to cause said lugs to ride beneath the ribs until the spring terminal 16 passes over and in rear of abutment 5. As the lug 12 which cooperates with the particular rib 4 having the abutment 5 is in assembling the parts positioned beneath said rib forward of the abutment and the spring terminal 16 positioned in rear of said abutment, it is evident that the cover is locked in relation to the box-body and can only be removed through breaking said spring or lug.

It will be noted that the use of the lugs on diametrically opposite sides of the cover will effectively prevent raising of the cover in the slightest degree and, furthermore, that the seating of the cover in the notch 11 of the body prevents tampering with the box contents or with the locking mechanism.

While it is preferred that the box and cover be constructed of metal to provide a simple inexpensive box, it is evident that it may be constructed of any desired material and may be arranged with various modifications of the above-described construction.

The invention of course is applicable to bottles, jars, boxes of various forms and configurations, and, in fact, all containing vessels in which it is desirable to preserve and insure 5 the purity and reliability of its original contents.

It will be noted that the spring 15 is of such length that when in contact with the locking-lug its surface intermediate its ends is normally close to the wall of the cover of the box, so that any strain tending to open the box will bend said spring with the result to break the wall of the cover, thus effectually destroying the box.

15 Having now described my invention, what I claim as new is—

1. A box formed with circumferentially-arranged ribs, and a cover therefor having means to engage one of said ribs to lock the 20 cover against movement in either direction.

2. A box formed with diametrically opposite ribs, an abutment projecting from one of said ribs, a cover to coöperate with said box, said cover being provided with lugs to engage 25 beneath the ribs and with means to engage said abutment.

3. A box comprising a body having a vertically-arranged neck, diametrically-arranged ribs formed on said neck, an abutment depending from one of said ribs, a cover arranged to inclose said neck, lugs projecting inwardly from the cover and adapted to ride

beneath the ribs, and a spring carried by the cover to engage said abutment.

4. A box comprising a body, a neck of less 35 diameter than said body and projecting therefrom, diametrically-opposed ribs arranged circumferentially on said neck, a cover equal in diameter to the diameter of the body, lugs projecting inwardly from said cover, and 40 adapted to ride beneath the ribs on the neck, and a spring carried by the cover and arranged to engage one of said ribs.

5. A box comprising a body, a neck of less diameter than said body and projecting therefrom, diametrically-opposed ribs arranged circumferentially on said neck, an abutment depending from one of said ribs, a cover equal in diameter to the diameter of the body, lugs 45 projecting inwardly from said cover and 50 adapted to ride beneath the ribs on the neck, and a spring carried by the cover and arranged to engage said abutment.

6. A box formed with a rib, a cover for the box, and means carried by the cover to engage 55 said rib to lock the cover against movement in either direction.

In testimony whereof I affix my signature in presence of two witnesses.

RICHMOND S. A. MOORE.
